UNITED STATES PATENT OFFICE.

OTTO SCHOTT, OF STUTTGART, GERMANY, ASSIGNOR TO WALTER GRUHLER, OF PANORAMASTR. 31, DEGERLOCH, STUTTGART, GERMANY.

FAUCET OR TAP FOR WATER PIPES, ETC.

Application filed August 29, 1923. Serial No. 660,001.

To all whom it may concern:

Be it known that I, Otto SCHOTT, a citizen of the German Republic, residing at Stuttgart, Wurttemberg, Germany, have invented certain new and useful Improvements in Faucets or Taps for Water Pipes, Etc., of which the following is a specification.

The invention has to do with a faucet of an already known outward construction that permits the removal of a regulating nozzle without shutting off the water supply elsewhere in order to replace a washer. This is made possible by a valve in the faucet itself, that turns off the water automatically.

The already known faucets have various disadvantages, for instance: Upon opening the faucet, the water not only flows through the proper outlet but also spurts through the threads that connect the nozzle with the main part of the faucet, and in that way wets the person using the faucet. This present invention contains a new form of valve that remedies the above disadvantage, all the water flowing downwards through the proper outlet.

Another improvement this faucet offers is the simplicity of the automatic valve, that does away with the disadvantages of the known cone or ball valves, which a single grain of sand etc., can cause to leak.

The drawing accompanying this specification illustrates the working of the invention and shows:

Figure 1, a longitudinal section as seen from the side of the faucet when closed.

Figure 2, a longitudinal section on line 2-2 of Figure 1, seen from the front of the faucet when open.

Figure 3, a longitudinal section of the automatic valve when shut.

Figure 4, the movable member of the lower valve as seen from the side.

Figure 5, the movable member of the lower valve as seen from below.

The ordinarily visible parts of the faucet consist of the delivery pipe "a" and the regulating nozzle "b", which latter screws over the free end of the delivery pipe; this nozzle is provided with several ridges "c" to insure a good hold.

A nipple comprising a plug "e" perforated by the hole "d" is screwed into the free end of the delivery pipe "a"; and according to my invention, both the plug and the hole

therein are of a larger diameter at the bottom than at the top, producing a bell-flange "f".

Above plug "e" is a cylindrical chamber "g", in which the invention provides for a freely movable leather, rubber, or the like disk "h" to open or close the passage "d".

The dimensions of chamber "g" are such; that the water is able to pass around the disk "h"; that the disk is adapted to shut the passage "d"; that the disk can not get out of its right position, that is to say, the disk will always be pressed down upon its proper seat whenever the nozzle is removed as shown in Figure 3.

Between delivery pipe "a" and regulating nozzle "b" there is a movable valve part, the lower end of which rests upon a small flat shoulder inside of the nozzle "b" and has a shape (for instance, like that of a cross "z") adapted to allow the water to pass freely between its extremities.

The general working method of this kind of faucet can be accepted as already known, which renders unnecessary any further description. My intention is rather to explain the advantageous results brought forth by the new arrangements in the present improvement.

These advantageous results already appear in the manufacture of the faucet, almost no work being required to form the upper automatic valve, since the boring that is necessary for the thread of the plug "e", need only be extended a short way to form the chamber "g".

By means of the free play allowed to disk "h", it is impossible for any foreign matter to rest upon the edge that supports the disk and impair the perfect functioning of the valve.

Another improvement that this faucet offers, is that the seat of the washer "v" is situated in the plug "e", so that the washer is entirely surrounded by a ring wall "f". In this way the water flowing from the valve does not immediately come in contact with the inner wall of the regulating nozzle "b", as it happens with the already known systems in which the water can easily go up through the threads. On the contrary, with the present faucet the water dashes against the wall "f", is thus directed downward and is prevented from passing through the threads

and escaping at the upper end of the nozzle.

What I claim as new, and for what I desire Letters Patent is:

1. In a faucet, a discharge pipe, a nozzle threaded thereon, a sleeve threaded in the lower end of said pipe, a bell flange on the lower end of said sleeve, a shoulder on the inner wall of said nozzle, a spider loosely supported on the shoulder, a packing member supported on said spider, said packing member arranged to seat in said flange whereby the packing member may be forced to and from an operative position by a rotary movement of said nozzle.
2. In a faucet, an exteriorly threaded discharge pipe, an interiorly threaded nozzle mounted thereon, a shoulder on the inner wall of said pipe providing an enlarged bore adjacent the lower end thereof, an externally threaded nipple mounted in the enlarged portion of said bore with the upper end thereof in spaced relation to said shoulder, a flat disk loosely mounted above said nipple, an annular shoulder in the wall of the bore of said nozzle, a closing member loosely mounted on said shoulder and a pin extending upwardly from said closing member and engaging said disk to hold the same in an open position.
3. In a faucet, a discharge pipe, an offset shoulder in the wall thereof to provide an enlarged bore at the end of the pipe, said pipe being internally threaded at the lower end thereof, an exteriorly threaded nipple operatively threaded in said pipe with the upper end thereof in spaced relation to said shoulder, a disk loosely positioned between said shoulder and said nipple, an internally threaded nozzle operatively threaded on said pipe and enclosing said nipple, a closing member supported by said nozzle and a pin projecting upwardly from said closing member and supporting said disk.
4. In a faucet, a discharge pipe, an offset shoulder in the wall thereof to provide an enlarged bore at the lower end of the pipe, said pipe being internally threaded from the lower end thereof to a point in spaced relation to said shoulder, an exteriorly threaded nipple operatively mounted in said threaded end of said pipe, the upper end of said nipple being positioned in spaced relation to said shoulder, a disk loosely positioned between said shoulder and the upper end of said nipple, said disk adapted to seat on the upper end of said nipple and close the bore, therein, said pipe being exteriorly threaded and an internally threaded nozzle member operatively mounted on the lower end of said pipe, an offset shoulder in the wall of the bore of said nipple, a spider supported by said offset shoulder, a pin coaxially fixed to said spider so as to project upwardly therefrom, a packing washer mounted on said pin and arranged to seat against the lower end of said nipple, whereby the nozzle may be rotated to open and close the lower end of said nipple, the upper end of said pin positioned against said disk whereby the same is held away from its seat in said nipple in the operation of said valve.

In testimony whereof I affix my signature.

OTTO SCHOTT.
